United States Patent Office

Des. 179,279

Patented Nov. 27, 1956

179,279

BOX

Jack Bloch, Leominster, Mass., assignor to Foster Grant Co., Inc., Leominster, Mass., a corporation of Massachusetts

Application April 10, 1956, Serial No. 41,017

Term of patent 14 years

(Cl. D58—12.6)

FIG. 1

FIG. 2

FIG. 3

FIG. 4

Fig. 1 is a top plan view of a box, showing my new design;

Fig. 2 is a side view thereof;

Fig. 3 is a front view thereof; and

Fig. 4 is a transverse cross-sectional view thereof, taken through the center of the box in open position.

I claim:

The ornamental design for a box, substantially as shown.
